UNITED STATES PATENT OFFICE.

SCIPION POUJOL, OF NEW YORK, ASSIGNOR TO M. H. BIRGE & SONS, OF BUFFALO, NEW YORK.

DESIGN FOR WALL-PAPER.

SPECIFICATION forming part of Design No. 23,623, dated September 4, 1894.

Application filed August 10, 1894. Serial No. 519,975. Term of patent 3½ years.

To all whom it may concern:

Be it known that I, SCIPION POUJOL, a citizen of France, residing at New York, in the county and State of New York, have invented and produced a new and original Design for Wall-Paper, of which the following is a specification.

The design consists of a series of vase-like ornaments filled with flowers and leaves with a series of ornamental scrolls at the base of said vase-like ornaments, and ornamental scrolls forming panels surrounding said vase-like ornaments, and festoons of flowers and leaves hanging from the ornamental scrolls as represented in the accompanying drawing. The border or upper portion of the design is also formed of similar vase-like ornaments filled with flowers and leaves, and ornamental

scrolls at the base of the vase-like ornaments, and ornamental scrolls surrounding said vase-like ornaments and forming panels, with festoons of flowers and leaves hanging from said scrolls as shown in the drawing. A narrow striped band separates the border from the hanging.

What I claim is—

1. The design for wall paper herein shown and described.
2. In the design for wall paper, the border herein shown and described.

Witness my hand this 8th day of August, 1894.

SCIPION POUJOL.
